UNITED STATES PATENT OFFICE

CLIFFORD S. GOBY, OF CLEVELAND, OHIO, ASSIGNOR OF ONE-HALF TO ALICE MYRZIE
DAVIS, OF NEW LONDON, OHIO

VALVE-OPERATING MECHANISM

Application filed April 18, 1927, Serial No. 184,541. Renewed August 30, 1929.

This invention relates to improvements in valve operating mechanisms and has reference particularly to operating mechanisms for rotating and reciprocating valves of cylindrical form, whether of the sleeve or piston type.

One of the objects of the invention is the provision of means for imparting to the valves of the character specified a continuous rotary motion and a reciprocatory motion imposed thereupon.

Rotating sleeve valves for internal combustion engines have certain advantages over those to which is imparted a simple reciprocating motion, for instance, it is possible to employ a single sleeve port for registration at the proper times with both the intake and exhaust ports of the cylinder, and thus the sleeve around the port is cooled by the intake between successive exhaust periods. Also the wear between the piston and the sleeve is more evenly distributed where the sleeve is constantly turning. However, a simple rotating movement does not lend itself well to good lubrication, and on this account I have devised the present invention in which is embodied all of the advantages of simple rotation and in which lubrication is more successful than in engines having either simple rotating sleeves or simple reciprocating sleeves. Furthermore, the operation of the valve is practically shockless, both the rotary movement and the reciprocatory movement approaching closely simple harmonic motion.

Other objects, and objects relating to details of construction and economies of manufacture, will appear as I proceed with the description of that embodiment of the invention, which, for the purposes of the present application, I have illustrated in the accompanying drawings, in which:

Fig. 1 is a vertical transverse sectional view through one cylinder of an internal combustion engine embodying my invention;

Fig. 2 is a longitudinal vertical sectional view of another engine showing a modification of the invention.

Referring first to Fig. 1, I have illustrated therein a rotary sleeve internal combustion engine having a cylinder 10 and a cylinder

head 11 provided with a threaded opening 12 for the reception of a spark plug. The cylinder exhaust port is shown at 13 and the intake manifold at 14, the intake port being located somewhat to one side of the 55 plane of the figure.

The valve sleeve is shown at 15 being provided in the case illustrated with two ports 16 and 17, the exact number and arrangement of the same being immaterial, however, so far as the present invention is concerned. The sleeve may be and preferably is provided on the outside with a spiral oil groove 18 running from a position near the bottom to a point well below the ports. 65

To the bottom of the cylinder block I bolt a casting 19 which is bored to constitute a continuation of the cylinder. In this casting I machine a bearing for a ring gear 20, which bearing has its axis in the line A—A at a 70 slight angle to the axis of the cylinder and sleeve indicated by the line B—B, the intersection of these two axes being in the plane of the ring gear 20, which is indicated by the line C—C. The angle between the lines A—A 75 and B—B may be varied within reasonable limits, thereby determining the extent of the vertical movement of the sleeve.

In assembling the parts, the gear 20 is slid onto its bearing and then a thrust collar 21 is threaded onto the casting 19 until a proper running clearance is obtained. 80

The teeth of the ring gear 20 mesh with the teeth of a gear 22 keyed to a shaft 23 arranged at right angles to the line C—C, the teeth 85 being either spiral or of the worm form shown in the drawing. The shaft 23, which takes the place of the usual cam-shaft or eccentric shaft of a multi-cylinder gas engine, is driven from the crank-shaft 24 by any convenient means, as by a chain, diagrammatically indicated at 25, running over sprockets on the two shafts. In the design illustrated, the shaft 23 revolves at the same speed as the shaft 24, but other speed ratios may be 90 employed without departing from the spirit of the invention. 95

Depending from the ring gear 20 is a projection 26 with an enlarged extremity in which is formed a spherical cavity to receive 100

a ball 27 pierced diametrically to receive with a sliding fit a pin 28 which is fixed in the lower end of the sleeve 15.

In the drawing, one of the cranks of the crank-shaft 24 is shown at 29, with a connecting rod 30 mounted thereon.

In operation, the ring gear 20 revolves freely on casting 19, and in doing so carries the projection 26 around the axis A—A. 10 Hence its distance from the axis B—B varies constantly, and there is a consequent slight motion constantly of the pin 28 in the ball 27. There is also a constant variation in the angle between the pin 28 and the projection 26, to which the ball and socket joint accommodates itself.

Obviously, the sleeve 15 has imparted thereto through its pin 28 a motion of rotation at a nearly constant speed, the variation 20 from constant speed being dependent upon the size of the angle between the lines A—A and B—B, and at the same time there is imparted to the sleeve a motion of reciprocation in a vertical direction. The variation in the 25 rate of rotational movement of the sleeve is not enough to affect unfavorably the timing of the engine, and in some cases might even be taken advantage of to favorably affect the quick opening and closing of the ports. The 30 vertical motion of the sleeve will also deviate somewhat from simple harmonic motion, but this fact is also of no importance inasmuch as the vertical motion is not depended upon for the opening and closing of the ports but 35 is provided for the sake of better lubrication.

The gearing 20, 22 will ordinarily be designed for imparting rotational movement to the sleeve at one-fourth the speed of the crank-shaft, and a consequent reciprocating 40 motion at the same speed. At this speed such secondary inertia forces as may be set up due to the slight variations from simple harmonic motion of the sleeve are too small to be of any consequence.

45 In Fig. 2 I have illustrated the application of my invention to the drive for a rotary valve, a plurality of cylinders in line being illustrated at 31, having ports 32 leading to the valve bore 9 in which is mounted a rotary 50 valve 33 having therein any suitable ports or passages for the intake or exhaust gases or both, one such port being illustrated at 34. The valve 33 projects through one end of the engine block 35 where it runs in a bore provided in an extension piece 36 which is secured to the casing 35 by bolts 37 or the like. A sprocket wheel 38 having its axis coincident with the axis of the valve 33 is mounted for free rotary movement on the extension 36 55 running between a shoulder 39 on the extension and a collar 40 threaded thereon.

The extension 36 is also machined to receive for rotational movement a ring 41, the principal plane of which, indicated by line 60 D—D, is set at an angle to the plane of the

sprocket wheel 38, the axis E—E of the ring being at a slight angle to the axis of the valve. The ring 41 may be held from displacement by a threaded collar 41'. On one side the ring 41 has ears 42 which carry a pintle 43. On this pintle is mounted for pivotal movement a pin 44 and an arm 45. The pin 44 slides in a hole 46 in the sprocket 38 with a somewhat "sloppy" fit necessitated by the fact that the angle of the pin 44 with the plane of the sprocket 38 is constantly changed. Arm 45 is universally connected at 47 with a projection 48 on the exposed end of the valve 33.

70 The sprocket 38 may be driven by a chain indicated diagrammatically at 49 either directly or indirectly from the engine crank-shaft. As the sprocket turns, the pin 44 of course revolves, carrying with it the pintle 43 on the ring 41. The arm 45 is thus rotated and transmits rotary motion to the valve 33 through the projection 48 thereon. Owing to the inclination of the ring 41, there is imparted to the valve 33 a motion of reciprocation also.

75 Having thus described my invention, I claim:

1. In a device of the class described, a cylindrical valve, means for imparting continuous rotary and reciprocatory motion thereto, comprising a ring surrounding the valve with its axis set at an angle to the axis of the valve, a bearing for said ring supported upon a fixed portion of the device, an arm connecting said ring with said valve, and means for rotating said ring.

80 2. In a device of the class described, a rotary and reciprocating valve, means for imparting continuous rotary and reciprocatory motion thereto, comprising a gear mounted with its axis intersecting the axis of the valve in the plane of the gear but inclined at an angle to the axis of the valve, an arm attached to the gear near the periphery thereof and to the valve, and means for rotating the gear.

85 3. In a device of the class described, a cylindrical reciprocating valve, means for imparting continuous rotary and reciprocatory motion thereto, comprising a ring gear surrounding the valve with its axis set at an angle to the axis of the valve, a bearing for said gear supported by a fixed portion of the device, an arm connecting said gear with said valve, and means for rotating said gear.

90 4. In a device of the class described, a cylindrical valve, means for imparting continuous rotary and reciprocatory motion thereto, comprising a ring surrounding the valve with its axis set at an angle to the axis of the valve, a bearing for said gear supported by a fixed portion of the device, an arm connection between said ring and valve embodying a universal joint, and means for rotating said ring.

5. In a device of the class described, a rotary and reciprocating valve, means for imparting continuous rotary and reciprocatory motion thereto, comprising a gear mounted with its axis intersecting the axis of the valve in the plane of the gear but inclined at an angle to the axis of the valve, connections between said valve and gear comprising an arm attached to said valve, and an arm attached to the gear near the periphery thereof, said connections embodying a universal joint, and means for rotating the gear.

10 6. In a device of the class described, a cylindrical reciprocating valve, means for imparting continuous rotary and reciprocatory motion thereto, comprising a ring gear surrounding the valve with its axis set at an angle to the axis of the valve, a bearing for said gear supported by a fixed portion of the device, a projection on said gear extending 15 parallel with the axis of the gear, a projection extending laterally from said valve, and a universal connection between said two 20 projections.

25 7. In a device of the class described, a cylindrical valve, means for imparting a continuous rotary and reciprocatory motion thereto, comprising a rotary element mounted with its axis of rotation intersecting the 30 axis of the valve in the plane of the rotary element but inclined at an angle to the axis of the valve, an arm attached to the rotary element near the periphery thereof and to the valve, and means for rotating said rotary element.

35 In testimony whereof, I hereunto affix my signature.

CLIFFORD S. GOBY.
